UNITED STATES PATENT OFFICE

ELMER E. BILLOW, OF EVANSTON, ILLINOIS

FURNACE

Application filed November 5, 1927. Serial No. 231,385.

The present invention relates to improvements in furnaces, particularly furnaces adapted to burn fuel such as powdered coal or oil.

5 The primary object of the present invention resides in the provision of a novel furnace having a variable combustion chamber.

In furnaces, particularly oil burning furnaces, subject to a variable demand, the supply of fuel may be regulated to vary the size of the flame from each burner nozzle. Thus, when one of these furnaces is being operated under a heavy load, the flame is relatively large, and when said furnace is being operated under a small or minimum load, or temporarily under no load, the flame is relatively small. In the last instance, the small flame is likely to be extinguished in the combustion chamber by draughts and because of the relatively low surrounding temperatures. As a result, the combustion chamber may become filled with unburned fuel vapors which may explode upon relighting the flame. An important object of the present invention therefore resides in the provision of a furnace having a relatively large main combustion chamber, a relatively small auxiliary combustion space or zone opening to said main combustion chamber, and means for so controlling the flame from the burner nozzle that it will burn in the main combustion chamber when large, but will be confined to the small combustion space when small, thereby in the last instance protecting it from draughts and maintaining it in a zone of relatively high local temperatures.

Another object resides in the provision of a furnace having a combustion chamber with a main combustion zone and one or more relatively small, contiguous and protected auxiliary combustion zones, with a burner in each of the latter.

A further object of the invention is to provide a furnace having a grate for admitting a stream of combustion air, a burner having a variable fuel supply and a constant air supply sufficient to maintain substantially complete combustion of a minimum fuel supply, and directed to flatten out the stream of fuel, and to confine it to a small zone contiguous

to the grate, and means for directing a blast of air against the stream of fuel mixture leaving the burner nozzle so as to direct the latter into the stream of combustion air over the grate.

Other objects of the invention are to provide a new and improved furnace in which there is an efficient and complete combustion of fuel, in which a homogeneous fuel mixture is obtained in the main combustion zone, in which the incoming combustion air is utilized to protect the walls of the furnace in the neighborhood of the combustion zone against excessive heat, in which the secondary air is admitted in such a manner that combustion takes place at substantial distances from the adjacent walls, in which the burners and various other parts of the structure are bodily adjustable for differently sized streams, and which is simple and relatively inexpensive in construction.

Further objects and advantages will become apparent as the description proceeds.

In the accompanying drawings, Figure 1 is a vertical sectional view of a furnace embodying the features of my invention, and taken along line 1—1 of Fig. 2.

Fig. 2 is a horizontal sectional view taken along line 2—2 of Fig. 1.

Fig. 3 is a horizontal sectional view taken along line 3—3 of Fig. 1.

Fig. 4 is a longitudinal sectional view of the burner nozzle taken along line 4—4 of Fig. 2.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

Referring to the drawings, I have shown the exemplary embodiment of my invention incorporated in a furnace structure having a vertical and preferably cylindrical combustion chamber 10, and mounted on a suitable

support 11, but it will be understood that the invention is applicable to different kinds of furnaces. In the present instance, the chamber 10 is defined by an inner cylindrical wall 12. Heating tubes 13 are suitably disposed inside and adjacent the peripheral wall 12. Preferably, a preheater for incoming combustion air is provided about the outside of the wall 12. In the present instance, the preheater comprises an annular space or chamber 14 defined about the wall 12 by an outer concentric wall 15, and closed at the upper and lower ends by annular end walls 16 and 17 respectively. A plurality of suitable tubes 18 extend longitudinally through the space 14 between the end walls 16 and 17. Of the tubes 18, the upper ends communicate with the combustion chamber 10, and the lower ends open into a suitable exhaust duct 19. A generally cylindrical slightly tapered baffle sheath 20 extends downwardly into the chamber 10, and serves to direct the products of combustion downwardly and over the heating tubes 13 before entering the tubes 18. Incoming combustion air is forced by means of a suitable fan 21 through an annular duct 22 into the lower end of the preheater space 14, and preferably the supply of air may be controlled or cut off by means of the fan. The construction thus far described taken by itself forms no part of the present invention, and is described for the purpose of fully illustrating the invention.

The present invention deals primarily with the burner section of the furnace, and with the control of the fuel and air supply to the combustion chamber 10. In the present instance, the burner section constitutes a dome or head 23 closing the upper end of the combustion chamber 10. To support the dome 23, preferably a plurality of vertical columns 24, four in the present instance, are secured in equally spaced relation on the support 11 and about the wall 15, and extend upwardly to the height of the wall 15 and somewhat above the wall 12. The columns 24, may be constructed in any suitable manner, as for example by securing two angle bars 25 together with two legs extending in directly opposite directions next to the wall 15, and by securing a strengthening strip 26 between the bars 25.

Secured in any suitable manner, as by angle bars 27, at its outer peripheral edge 55 to the inside of the wall 15 near its upper end, is an annular horizontal wall 28 which projects over the wall 16 and in spaced relation thereto. The inner peripheral edge of the wall 28 is turned downwardly to form a depending cylindrical flange 29 which extends into the sheath 20 and over the inner upper coils of the heating tubes 13 to protect the latter from excessive heat. The upper end of the sheath 20 is secured to the 65 underside of the wall 28 by means of an angle

rim 30 concentric with the flange 29, thereby sealing the space between the upper end of the sheath and the wall 28 so as to direct all of the products of combustion downwardly over the lower end of the sheath.

Secured to the wall 28 in any suitable manner and in equally spaced relation along its inner peripheral edge are a plurality, four in the present instance, of upwardly and inwardly inclined arcuate walls 31. Secured to the side edges of the walls 31 in any suitable manner are a plurality of U-shaped wall members having side walls 32 and a top wall 33. The lower edges of the side walls 32 rest on the wall 28. The U-shaped wall members define compartments 34, four in the present instance, the inner ends of which open into the combustion chamber 10, and which constitute relatively small auxiliary combustion chambers forming part of the combustion chamber 10 but not subject to the draughts therein. Preferably, the compartments 34 are located intermediate the columns 24.

Secured to the upper ends of the columns 24 and in abutting relation with the upper edge of the wall 15 are a plurality of arcuate members each having a horizontal wall 36 parallel to the wall 28, and an upwardly and inwardly inclined wall 37 parallel to one of the walls 31. The walls 36 and 37 are suitably spaced from the walls 28 and 31 by spacers 38 to define air passages 39, and the parts are held in assembled relation by any suitable means such as bolts 40. Suitable inwardly extending arms 41 secured to the columns 24 and the walls 36 by any suitable means such as angle plates 42 are secured to the walls 37 as by welding to support the latter.

Secured to the side edges of the walls 37 as by welding are a plurality of U-shaped wall members each having side walls 43 and a top wall 44 held in spaced relation respectively to the walls 32 and 33 to define an air space 45 therewith about the compartments 34 and opening into the passages 39. The side walls 43 rest on the walls 36. Suitable spacer members 47 are secured between the inner and outer walls of the air spaces 45, and the parts are clamped together by means of bolts 48. Suitably secured to the outer ends of the U-shaped wall members are a plurality of end walls 49 which close the outer ends of the compartments 34 and the air spaces 45.

Formed on the upper end of the wall 15 between the columns 24 are a plurality of arcuate chambers 50 each having an outer arcuate wall 51, end walls 52 and a bottom wall 53. The upper edge of the wall 51 is secured to the underside of the wall 36, and the inner edges of the walls 52 and 53 are secured to the outside of the wall 15. The chambers 50 communicate through openings 54 and 55 respectively to the chambers 14 of the preheater and the compartments 34 and air passages 39.

Projecting into the outer ends of the compartments 34 are a plurality of suitable burners 56, one for each compartment. In the present instance, each burner 56 comprises a water cooled nozzle 57 longitudinally adjustable in a sleeve 58 in the end wall 49, and adapted to discharge a stream of a suitable fuel and air, such as fuel oil and air.

Referring to Fig. 4, the nozzle 57 preferably comprises a discharge orifice 68. A tube 69 opening at the orifice 68 is adapted to be connected through a hand control valve 70 to a fuel supply pipe 71 adapted to be connected to a suitable source (not shown). Surrounding the tube 69 is a sleeve 72 which is open to an air supply line 73 adapted to be connected to a suitable and preferably constant source of air under pressure (not shown). The sleeve 72 opens about the tube 69 to the orifice 68 and also to an air discharge orifice 74 at one side of the former. The orifice 68 thus is adapted to direct a stream of fuel and air horizontally into the main combustion chamber 10. The orifice 74 opens downwardly, and is adapted to discharge a stream of air against the stream of fuel to flatten the latter and to direct it downwardly at an angle onto the bottom wall of the chamber 34. The air supply through the pipe 73 is such that when the supply of fuel is adjusted to a minimum for a small flame, it will be sufficient to produce substantially complete combustion. To protect the wall 28 from excessive heat, a plate 59 is adjustably mounted on and in spaced relation to the wall 28. This plate is held in position by suitable guide members 60 and has an arm 61 extending outwardly through the walls 15 and 51 by which it can be adjusted. The plate 59 is so adjusted that the flattened stream of fuel and air from the burner 56 will impinge thereon unless raised out of contact therewith as will be hereinafter described. The plate 59 becomes highly heated, and hence serves to aid in keeping a small stream ignited.

Means is provided for directing the air entering through the openings 55 into the chamber 34 over the plate 59 and against the underside of the fuel stream so as to raise the latter from the plate 59 and direct same into the combustion zone in the chamber 10. This means comprises a baffle plate 62 suitably secured to the inside of the wall 15 just over the opening 55, and slightly inclined downwardly to a point over the plate 59.

Mounted in the center of the dome 23 is a suitable grate 63 for supplying the necessary combustion air to the chamber 10. Preferably, the grate 63 is round and has a peripheral flange 64 at its upper edge resting on the upper and inner edges of the walls 31 and 33. The opening at the upper and inner edges of the walls 37 and 44 directly over the grate 63 is closed by a suitable plate 65. The grate 63 and the plate 65 define an air chamber 66

which communicates with the air passages 39 and the air spaces 45. It will thus be noted that all of the inner surfaces of the dome 23 exposed to direct heat are air cooled. The center of the grate 63 is formed with suitable air inlet means, such as a plurality of perforations 67, to admit a central blast of air to the combustion chamber 10. Preferably, the center of the pan 63 is pressed inwardly or upwardly to orientate the perforations 67 toward the center of the chamber 10 so as to keep the flames from impinging directly on the inner coils of the tubes 13. To prevent the flame from any one of the four burners 56 from entering or coming close to one of the other burners, the grate 63 is formed in the shape of a pan depending into the upper end of the chamber 10.

In operation, when the furnace is under a load, air is supplied by the fan 21 to the chambers 34 and the grate 63. The air passes through the grate 63 into the combustion chamber 10. Each burner discharges a flattened stream of fuel with some air, and this stream is directed by the air entering the chamber 34 into the main combustion chamber 10 and the stream of air from the grate 63 where it is consumed. The incoming air while itself at a high temperature still serves to cool the inner walls of the dome 23.

When there is temporarily no load or a very small load the supply of fuel to each burner 56 is reduced thereby causing the flame to withdraw into the small chamber 34. The supply of air to the chamber 34 is stopped so as to permit the small flattened stream of fuel from the burner 56 to impinge on the hot plate 59. With the fuel supply reduced to a small stream, enough air enters through the nozzle 58 to effect complete combustion in the chamber 34. Thus the small stream of fuel burns quietly without smoking in the chamber 34, and is protected from the draughts and lowering temperatures in the main combustion chamber 10. The chamber 34 being small is readily maintained at a relatively high temperature. If the small flame were in the main chamber 10, it probably would soon be snuffed out, and the chamber 10 would fill with unburned vapors so that explosions might result.

It will be evident that the construction is simple and inexpensive, that there will be no over-heating of the parts, and that a homogeneous fuel mixture and hence complete combustion will be obtained. The parts described herein can be made of any suitable material, but preferably metal highly resistant to injury from heat is employed.

I claim as my invention:

1. A furnace having, in combination, a relatively large combustion space, a relatively small auxiliary combustion space, a burner opening to said small space, and means for controlling the flame from said burner to

direct it to said large space when full and to confine it to said small space when small.

2. A furnace having, in combination, a combustion chamber having a central combustion zone and an auxiliary confined combustion zone, a burner, and means for selectively directing the flame from said burner to said main zone or for confining said flame to said auxiliary zone.

10. 3. A furnace having, in combination, a combustion chamber, a burner having a variable fuel supply and a constant air supply sufficient to maintain substantially complete combustion of a minimum fuel supply, and having means for directing the air in a jet across the fuel jet to flatten and deflect the latter against one wall of said chamber, and means for directing a stream of fluid against the underside of said fuel jet to keep the latter away from said wall and to direct it to without said chamber when desired.

4. A furnace having, in combination, a combustion chamber, a wall forming part of said chamber, a plurality of spaced and double-walled compartments formed in said wall and opening into said chamber, a plurality of burners one in each compartment adapted to direct a stream of fuel into said chamber, a depending member in said wall between said burners, and formed with air inlet means, and means for directing air through said compartments into said chamber, and air over said wall through said member into said chamber.

35. 5. A furnace having, in combination, a combustion chamber, a wall forming part of said chamber, a plurality of spaced compartments formed in said wall and opening into said chamber, a plurality of burners one in each compartment adapted to direct a stream of fuel into said chamber, a depending member in said wall between said burners, and formed with air inlet means, and means for directing air over said wall through said member into said chamber.

40. 6. A furnace having, in combination, a combustion chamber, a wall forming part of said chamber, said wall being formed with a plurality of distinct, relatively small and spaced chambers opening to said combustion chamber, and a plurality of burners one mounted in each of said spaced chambers and adapted to direct a stream of fuel mixture therefrom into said combustion chamber.

45. 7. A furnace having, in combination, a combustion chamber, a wall forming part of said chamber, said wall being formed with air inlet means, means for directing air over the outside surface of said wall to said inlet means, and a plurality of burners mounted in said wall in spaced relation about said first mentioned means.

8. A furnace having, in combination, a combustion chamber, means forming an auxiliary combustion space distinct from and

opening to said chamber, and a burner adjustably mounted in said space, said burner having means for adjusting the fuel supply so as to vary the flame from a size extending into said chamber to a size substantially confined to said space.

9. A furnace having, in combination, a combustion chamber, a dome closing said chamber, said dome being formed with a plurality of spaced compartments opening into said chamber, and having double walls defining air filled spaces, and a plurality of burners one mounted in each compartment and adapted to direct a stream of fuel therethrough into said combustion chamber.

10. A furnace having, in combination, a combustion chamber, a relatively small compartment opening to said chamber, a burner adapted to discharge a stream of fuel into said compartment and against a wall of said compartment, means for adjusting the fuel supply to said burner, and means for directing a stream of air over said wall to raise said stream of fuel therefrom and direct it into said chamber.

11. A furnace having, in combination, a combustion chamber, a wall forming part of said chamber, a plurality of spaced compartments in said wall and about said chamber, a plurality of burners one in each compartment and means for directing air through said compartments into said chamber.

12. A furnace having, in combination, a vertical chamber, a wall closing the upper end of said chamber, a plurality of burners mounted in spaced relation in said wall and about said chamber, a member mounted centrally in said wall and depending between said burners, and means for directing air over the outer surface of said wall and through said member into said chamber.

13. A furnace having, in combination, a vertical combustion chamber, a plurality of supporting columns disposed about said chamber, a wall supported on said columns and closing the upper end of said chamber, a plurality of compartments formed at the periphery of said wall and opening therethrough into said chamber, a plurality of burners one in each compartment and adapted to direct a stream of fuel into said chamber, means for directing air through said compartments into said chamber, and means for directing air over said wall into said chamber.

14. A furnace having, in combination, a furnace chamber having a central draft having a space out of the central draught, adjustable means disposed in said space, a burner having a nozzle adapted to direct a stream of fuel against said means, and means for directing air over said means to carry said fuel out of said space into said furnace chamber.

15. A furnace having, in combination, a combustion chamber, a compartment opening into said chamber, means mounted on and in

spaced relation to the bottom wall of said compartment, said means being adjustable lengthwise of said compartment, a burner having a nozzle adjustably mounted in said compartment and adapted to direct a stream of fuel therefrom against said means, and means for directing a stream of air over said first mentioned means to remove said stream of fuel therefrom and direct same into said chamber.

10 16. A furnace having, in combination, a combustion chamber, a compartment, a burner in said compartment adapted to direct a stream of fuel therefrom into said chamber, a plate mounted on the bottom wall of said compartment, and means for directing a stream of air between said plate and said burner to raise said stream from said plate.

15 In testimony whereof I have hereunto affixed my signature.
